TYPEWRITING MACHINE

Miles H. Mann, West Hartford, Conn., assignor to
Underwood Elliott Fisher Company, New York,
N. Y., a corporation of Delaware

Application January 15, 1942, Serial No. 426,828

17 Claims. (Cl. 197—126)

This invention relates to typewriting machines and more particularly to machines usually referred to as fanfold or continuous billing machines, wherein carbon sheets are supported in interleaved relation between continuous webs, or the plies of a fanfolded web, and are shiftable or retractable therealong for registration with succeeding web portions or forms.

Patent No. 2,275,782, issued to Miles H. Mann, dated March 10, 1942, features such a machine equipped with a power mechanism for retracting the carbon sheets, and it is a major object of the present invention to improve upon the machine of the said application.

Although, as in the said prior application, the various features of the invention are shown applied to a machine embodying the structure shown in the patent to Wernery and Smith No. 1,132,055, dated March 16, 1915, they are to be regarded as applicable also to other writing machines, particularly such wherein carbon sheets are successively registered with succeeding portions of a continuous work web.

It is another object of the invention to provide an improved motor-driven carbon-retracting device.

A further object of the invention is to provide durable and inexpensive transmission means whereby a stationarily located motor may actuate a carriage-supported carbon-retracting device.

It is also an object of the invention to produce improved controlling devices whereby a motor-driven carbon retracting device is adapted to be rendered effective and ineffective.

A further object of the invention is to furnish efficient automatically-acting means to prevent rebounding of the carbon-carrier after its retraction to a certain position.

Another of the objects of the invention is to provide a simple and efficient carbon-retracting device which is normally biased to advance the carbons.

Still other important objects and features of the invention will be apparent upon consideration of the detailed description which follows, as that description is read in the light of the accompanying drawings.

Referring now to the drawings:

Figure 1 is a general perspective view of a typewriting machine embodying the invention.

Figure 2 is a sectional side view taken near the right-hand carriage end, and illustrating a mechanism operable by a paper-gage-bar to release a platen sub-frame for displacement.

Figure 3 is a right-hand sectional side elevation showing a carbon carrier in an advanced position upon a typewriter carriage, a portion of a leading form having been typed upon,

5 Figure 4 is a view similar to Figure 3 but shows the carbon carrier at the moment of full power-retraction,

Figure 5 shows diagrammatically a motor and circuit controls therefor,

10 Figure 6 is a fractional plan view of a portion of the carbon retracting mechanism, the retracting mechanism being idly conditioned,

Figure 7 is a sectional front view taken approximately along line 7—7 of Figure 6, showing a portion of the carbon retracting device,

15 Figure 8 shows a transverse section through a belt drum constituting part of the carbon retracting device,

Figure 9 is a fractional plan view of a mechanism whereby carbon retracting motion is transmitted from a stationarily located motor to a carbon retracting mechanism on the carriage,

20 Figure 10 is a fragmentary plan view and shows the carbon retracting device ineffectively conditioned as a result of the retraction of the carbon carrier, and further shows a device effectively conditioned to check forward rebounding of the carbon carrier,

25 Figure 11 is a fractional plan view which illustrates certain controlling devices for a clutch of the carbon retracting device in normal position,

Figure 12 shows a portion of the mechanism shown in Figure 10, the clutch having been closed by the operation of the controlling devices, and

30 Figure 13 illustrates a dash-pot control which forms part of the rebound checking device for the carbon carrier.

Referring now particularly to Figure 1, a carriage 10 is mounted to travel upon front and rear rails 11, 12 of a stationary typewriter frame, generally designated by the numeral 13. A usual spring motor, not shown, moves the carriage in letter-feed steps in response to each typing impression made by type-bars 15. The illustrated carriage 10 comprises a main frame 16, a case-shiftable frame 17 within the carriage frame 16, and a pivotally displaceable sub-frame 18 carrying a writing support in the form of a platen 21.

35 The frame 17 is case-shiftably mounted within the main carriage frame 16, in a manner not shown, but as is usual in Underwood typewriting machines, and comprises end plates 22 connected by several cross bars, one of which is indicated at 23 in Figures 2 and 3. The displaceable sub-frame

18 is shown to include two opposite end pieces 24 rigidly connected by a bar 25, see Figures 2 and 3. The displaceable sub-frame 18 is normally located within the case shift frame 17 so that the platen 21 bears upon front and rear feed rolls 26 and 27, respectively, see Figures 2 and 3. The sub-frame 18 is pivotally supported by means of studs 28 extending inwardly from the case-shift frame end-plates 22 into the end pieces 24. At the rear of the platen, the end pieces 24 of the sub-frame 18 seat normally upon collars 29 provided upon a rod 32. The rod 32 is pivoted in the opposite end plates 22 of the frame 17 and has near each of its opposite ends a latch arm 31 secured to it. Each arm 31 has a hook formation 33 that normally overlies a pin 34 on an end piece 24 of the sub-frame to hold the latter down. The hook or latch arms 31 are rearwardly swingable to clear the pins 34 and to render thereby the said sub-frame 18 displaceable to the position seen in Figures 5 and 4. A spring 35 by engaging a downwardly extending branch 36 on one of the arms 31 tends to swing the arms 31 forwardly into latching position, the downwardly extending branch 36 limiting the forward motion of the latch arms by engagement with the bar 23. The platen 21 is rotatable within the displaceable sub-frame 18 by means of a spindle 37, the spindle extending through the end plates 24 of the sub-frame 18 and having at each end a gear 38 secured to it. Adjacent to each gear 38 is another gear 41 secured to a stub-shaft 42 which is revolvably mounted upon the adjacent case-shift-frame end-plate 22. As seen in Figure 1, there is provided upon each end of the carriage, another gear 43 meshing with one of each of the gears 38 and 41. Each stub shaft 42 is revolvable by a knob 44; and since each gear 43 is in mesh with a gear 38 and a gear 41, the platen 21 is revolvable by turning either one of the knobs 44.

Attached to the rear of the carriage 10 is a rectangular extension or shelf 45, formed of light-gage sheet metal and having weight-reducing openings 46. This extension is formed with downwardly-turned flanges 47 along the periphery and also along said openings 46 to stiffen it. At the forward end, the extension 45 is slidably carried for small laterally limited movements upon a rod 48 extending intermediate two spaced brackets 51 reaching rearwardly from the typewriter carriage 10. The brackets 51 are secured to a rear bar 49 of the main carriage frame 16, and the carriage extension 45, therefore, does not case-shift with the case-shift frame 17. Rearwardly of the carriage 10, the extension 45 has secured to it a downwardly reaching bracket 52 carrying a plurality of laterally spaced rollers 53 adapted to run in a channel bar 54 secured to a framework 55 extending from the rear of the typewriter frame 13 and comprising two rearwardly extending triangular plates 56 secured to the rear portion of the main typewriter frame 13.

The rod 48 at the back of the carriage 10 extends through holes 50 provided in the peripheral flanges 47 of the carriage extension 45, and the movement of the latter upon the rod 48 is limited by collars 65 fastened upon the rod, one at each lateral side of the extension in slightly spaced relation thereto. The extension 45 is resiliently carried along by the carriage by means of two springs 67, each spring having one end secured to a stud 68 on the rod 48 and having another end secured to the underside of the carriage extension 45. The springs 67 extend in opposite directions from the stud 68 and are designed to urge the ex-

tension to assume a definite position with respect to the carriage while, however, permitting the extension 45 to lag momentarily behind the carriage during each letter-feed movement of the carriage. The typewriter carriage 10, therefore, letter feeds substantially without interference by the mass of the extension 45 and the parts carried thereby, and thus permits utmost typing speed. The collars 65 forceably compel the carriage extension 45 to move with the carriage during long carriage advance and long carriage return movements. At the termination of such long movements, the springs 67 cushion the arrest of the extension.

A conventional carbon carrier unit 69 comprises a truck plate 71 and a capping plate 72 overlying the truck plate, the latter being secured upon the former in a readily detachable manner, not shown, but conventional in Underwood fan-fold machines. The truck plate 71 has at each lateral end a pair of grooved rollers 73 engaging the outer edges of parallel trackways 74, the latter extending along the left and right border of the carriage extension 45. The capping plate 72 has fastened upon each of its lateral ends a stepped bracket 75, and attached to these brackets are blades 76 whereto carbon sheets 81 are attached in a conventional manner, see Figures 3 and 4.

Referring now to Figures 1 and 3, the work web 83 is supplied upwardly from the rear of the machine over a guide bar 77 and extends forwardly over the carriage extension 45 and downwardly around to the front of the platen 21. The case shift frame 17 supports a usual paper apron 82, and the displaceable sub-frame 18 has a paper table 84 extending tangentially from the upper front portion of the platen 21, as seen in Figures 1, 2 and 3. A form severing knife 85 is also carried by the sub-frame 18, see Figures 1, 3 and 4. The work web 83 may comprise several plies 86 and the carbon sheets 81 extend forwardly from their supporting blades 76 in interleaved relation with the plies, the leading ends of the carbon sheets being normally about $\frac{1}{2}$ inch short of the leading ends of the work plies. Figure 3 shows the work web in an advanced position so that the leading end of the work web is above the cutting edge of the knife 85 and so that the carbon carrier unit 69 is an appreciable distance forward of a stop 88.

As already has been brought out, the platen is rotatable to advance the work web 83 by means of knobs 44. The platen may be rotated in line-spacing steps in any known manner, either manually or by power. There is illustrated in Figure 9 a portion of a power actuable carriage return and line-spacing mechanism which may substantially correspond to the patent to Pitman No. 1,679,741, dated August 7, 1928, and which may include a rack 91 limitedly slideable on the carriage 10, in a manner not shown. The rack 91 is geared to a power rotatable pinion 92, which, when power rotated, advances said rack 91 in carriage return direction, first to line space the platen 21 and thereafter to return the carriage. The pinion 92 has clutch teeth 93 normally disengaged from a clutch member 94 that may be continuously driven by a motor 95 through intermediate transmission members that may comprise a shaft 97 and a worm gear drive 98, see Figure 9. To effect a line-spacing and a carriage returning operation, it is merely necessary that the pinion 92 be shifted to engage its teeth 93 with the clutch member 94. This, as is evident from said above-

mentioned Pitman patent, may occur responsive to depressing a carriage return key, or responsive to the carriage reaching a definite position in its advance.

The carbon sheets are shifted from time to time to register with the succeeding forms to be typed upon. This is preferably done with the web in a straightened position so that the web plies will not bind the carbons. Accordingly, when it is desired to shift the carbons 81 to register with a set of succeeding forms, the latches 31 are first moved clear of the pins 34 and thereafter the sub-frame is swung upwardly and forwardly to raise the platen 21 above the general plane of the carriage extension 45. See Figure 4. In the embodiment of the invention shown, means are provided to effect this by a single continuous motion of the operator's hand. More particularly, as seen in Figure 2, a bar 101 supporting an adjustable paper-gage 102 is limitedly displaceable in a forward direction upon said sub-frame 18; and when so displaced, causes the latch arms 31 to be moved clear of the pins 34. Continued forward movement of the gage bar 101 displaces the sub-frame 18 about its pivot studs 28. Viewing Figure 1, it can be seen that the gage bar 101 is fastened between the ends of the carriage to a pivoted shaft 103 extending toward the right end of the sub-frame 18, whereat, see Figure 2, the shaft 103 carries fixedly an arm 104. Brackets 105 secured to the back of the bar 25 provide pivotal supports for the shaft 103, and a spring, not shown, urges the gage-carrying bar 101 to normally occupy the position seen in Figures 1, 2 and 3 against an abutment, not shown. As seen in Figure 2, the arm 104 extends normally rearwardly from the shaft 103 and carries a pawl member 111. This member 111 is engageable with a pin 110 on one of the latch arms 31 to swing the latter, together with the other latch arm 31, rearwardly when the gage bar 101 is given an initial forward motion. During continued forward motion, the gage bar 101 lifts the sub-frame 18 by engaging the bar 25 thereon, so that finally the sub-frame comes to rest upon the forward part of the main carriage-frame 16. The gage bar 101 and the sub-frame 18 will then occupy substantially the position illustrated in Figure 4, it being noted that the gage bar may reassume its normal position with respect to the displaceable frame 18, sometime during the displacement of the latter. The distance from the edge of the knife 85 to the gage 102 is equal to the length of the forms used and, to bring the carbons into register with succeeding forms, the carbons are retracted relatively to the web a distance equal to a single form length. This is accomplished by advancement of the work web 83 against said paper gage 102 accompanied by the shift of the carbon carrier unit 69 against the stop 88. The work web 83 is preferably advanced against said gage 102 incidental to moving the gage bar 101 forwardly to raise the sub-frame 18. To this end, the operator lightly pinches the leading end of the web plies 86 and the gage bar 101 between the thumb and index finger and swings the gage bar 101 forwardly while also sliding the fingers along the gage bar to advance the leading ends of the plies to the gage 102.

Power retraction of carbon carrier

Normally ineffective power retracting means are provided for said carrier unit 69, which means are preferably rendered effective incidental to

displacing the said gage bar 101 to raise the sub-frame 18. Directing attention more particularly to Figures 6 to 12, this power retracting means will now be described.

- 5 Upon the underside of the carriage extension 45, there is mounted a drum 115, capable of driving a belt or its equivalent 116 for retracting the carbon carrier unit 69. The belt 116, according to the embodiment of the invention shown, is
- 10 attached at 117 to a bracket 118 reaching downwardly from said carbon carrier truck plate 71, and extends from said point of attachment oppositely fore and aft onto a front pulley 121 and a rear pulley 122 from which pulleys the belt is
- 15 directed oppositely onto the drum 115. In order to associate the belt positively with the drum, the belt has two ends which are oppositely wound upon the drum, one above the other; the drum, for this purpose, being at least double the width
- 20 of the belt. From the foregoing, it will be evident that opposite rotational motions of the drum 115 will result in opposite directional movements of the belt 116, and consequently, the carbon carrier unit 69. The drum 115 is lightly constructed and
- 25 may consist of the two spaced sheet-metal flanges 123 seen in Figure 7, joined by the thin hollow cylinder 124 seen in Figure 8. The cylinder 124 is slotted at 125 for admittance of the opposite ends of the belt within the hollow cylinder onto
- 30 any one of several anchorage pins 126 carried by one of the flanges 123. The entire drum 115 is rotatably mounted upon a short arbor 127 and a spiral spring 128 situated between the drum flanges 123 has one end anchored to the arbor
- 35 and another end anchored to any one of several ears 131, the ears being bent at right angles from one of the drum flanges and forming, together with the flanges 123, a cage within which the spiral spring 128 is confined. See Figure 8. The
- 40 spiral spring 128 is so mounted and tensioned that the drum 115 urges the belt to advance the carbon carrier 69. Preferably, the tension of the spring 128 is such as to counterbalance the drag of the paper web and also the inertia and friction of the carbon carrier 69 which normally opposes forward movement of the carbon carrier. In other words, the spring is so tensioned that the carbon carrier will move forwardly upon the least application of force. For rendering the
- 45 spring 128 conveniently adjustable for different weights of carbon carriers and webs, the short arbor 127 is rotatable in upper and lower bracket plates 138 and 141, respectively and has an integral spiral gear 132 whereby it is rotatable
- 50 through a worm shaft 133 which is provided with a knob 145.

The upper bracket plate 138 is mounted upon studs 142 which are fixed and reaching upwardly from the lower bracket plate 141, the latter being

- 60 fastened to the underside of the carriage extension through the medium of spacing studs 143. Bent down from the upper bracket plate 138 are front and rear ears 144 wherein the said worm shaft 133 is rotatably supported. As may be seen in Figure 1, the upper bracket plate is situated in one of the openings 46 of the table 45, and the worm shaft turning knob 145 is easily accessible for effecting adjustments to the spring 128.
- 65

The rear pulley 122 is pivoted on a headed stud 70 134 secured to a block 135 provided on the underside of the carriage extension or table 45, while the front pulley 121 may be carried by an arm 136 for swinging movement therewith about one of the studs 143, the arm being under constant tension of a spring 137 to keep the belt 116 taut.

From time to time it is desired to retract the carbons 81 with respect to the work web 83, as in preparation for typing upon a new form; and, in order to accomplish this expeditiously as well as efficiently, the aforesaid motor 95, aside from being capable to return the carriage 10, also is adapted to rotate the said belt drum 115 to retract the carbon unit 69. To this end, the motor shaft 97 is extended rightwardly from the worm gear drive 98 and carries a transmission pulley 146 which, through the medium of an endless belt 147, drives a pulley 148. A shaft 151 extending parallelly to the carriage 10, revolves unitarily with said pulley 148 and has splined thereupon a sleeve in the form of a clutch member 152 which is adapted to partake in the carriage movements by sliding along the said shaft 151. The shaft 151 is preferably of square cross section and the clutch member 152, in order to slide with the least resistance along the shaft 151, may have rollers 153 engaging the four flat sides of the shaft. See Figure 9. During the movements of the carriage 10, the clutch member 152 is caused to move unitarily with the carriage through a clutch shifting element 154 which is pivotally carried on the lower bracket plate 141 but normally held stationary with respect thereto, against a dog 156, by a contractile spring 157, see Figure 11. Leftwardly of the clutch member 152 and coaxial therewith is another clutch member 158 comprising a gear 161 which is in constant mesh with a gear ring 162 fixedly carried by the lower flange 123 of the belt drive drum 115. The clutch members 158 and 152 have normally disassociated clutch teeth 164 facing toward each other. Directing attention to Figure 9, it will be seen that the member 158 is rotatably carried upon a hollow stud 165 which is secured at 166 to a right angularly bent bracket 167 riveted to the underside of the bracket plate 141 as at 168. An enlarged portion 171 of the stud cooperates with the bracket 167, to confine the rotary member 158 to move with the carriage extension 45. The square shaft 151 passes through the hollow stud, and has preferably some clearance therein. A reduced portion 169 of the hollow stud fits into the clutch member 152 to give the latter a firm bearing support, whereby the rollers 153 in turn provide an intermediate support for the shaft 151.

From the foregoing, it will be seen that the typewriter carriage with its extension can move freely, the clutch members 152 and 158 being adapted to move with the carriage and being adapted to be brought into clutching engagement in any position of the carriage. Supporting the shaft 151 may be a bracket structure comprising two bars 172, one in front and one in back of the shaft 151, both extending parallelly to the carriage, the bars being fastened by screws 173 to the framework plates 56 and carrying at each end a hanger 174 for supporting the shaft 151. The shaft may have a reduced end pivoted in the left hanger; and, at the right, the shaft may be pivoted in a bearing 175 screwed into the hanger 174 and projecting outwardly therefrom. To relieve stress upon the shaft 151, the pulley 148 may run upon the said projecting bearing 175. The pulley 148 has a hub 176 into which the square shaft 151 fits and the pulley may be prevented from slipping off the shaft by a pin 179. A collar 177 may cooperate with the pulley 148 to retain the shaft 151 against lateral movement. It should be understood that the shaft 151 is of sufficient length to allow full range travel of the

typewriter carriage 10. Although the shaft 151, according to the preferred embodiment of the invention, revolves continuously, the clutch member 158 is normally free to revolve, as, for example, during advancement of the carbon carrier caused by turning the platen 21. For rendering the motor 95 operative to retract the carbon carrier 69, the clutch shifting element 154 is given over to the urge of its spring 157 by operation of the dog 156 to the position seen in Figure 12. Thus, the clutch member 152 is resiliently moved into driving relation with the companion clutch member 158; and as a result, the gears 161 and 162, and, therefore, also the drum, commence to be driven by the motor 95, resulting in the retraction of the carbon carrier 69 through the operation of the belt 116.

Although the dog 156 may be operated in any suitable manner, this is preferably done as an incident to the displacement of the platen sub-frame 18 through a mechanism presently to be described with more particular reference to Figures 3, 4, 11 and 12. Adjacent the left end of the displaceable sub-frame 18, see Figure 3, just leftwardly of the gear 43, is a finger 178 embracing one of the sub-frame pivoting studs 28 and having an upper end secured to the left sub-frame end-piece 24. The finger 178 is unitarily displaceable with the sub-frame 18 about the pivot stud 28 and has, at a point below and rearward of the stud 28, a link 181 connected thereto. The link 181 extends rearwardly and is articulated at its rear end to a horizontally disposed arm 182 comprising part of a bell crank structure which further comprises a vertical shaft 183 and a lower, rearwardly extending arm 184. The shaft 183 pivots in an upright bushing 185 fixed upon the left bracket 51 extending rearwardly from the typewriter carriage proper. Articulated to and reaching rightwardly from the arm 184, is a link 186 which is capable of operating a parallel motion linkage comprising two spaced arms 187 and connecting link 188 for said arms, the latter having a slot 191 extending in parallelism with the carriage 10. The arms 187 are pivoted at two spaced points 192 to the underside of a bar 193 which is rigidly carried by the rod 43 through the medium of blocks 194. A dog controlling element 195 pivoted on the bracket plate 141 has an upright pin 196 located in the link slot 191 and another pin 197 is adapted to release the dog 156 from the aforesaid clutch shifting element 154 whenever the platen sub-frame 18 is being displaced. It should be observed at this point, that the link 188 with its slot 191 affords an operating connection for said dog controlling element 195 which is operative irrespective of the position of the carriage extension 45 with respect to the carriage proper 10. Whenever the platen is displaced to the position seen in Figure 4, the link 181 receives an initial slight rearward movement, and thereafter a forward movement of greater magnitude. The initial slight rearward movement of the link 181 is of an idle nature in that it has no influence whatever on the dog 156. The final forward movement of the link 181, as brought about by the sub-frame 18 approaching the displaced position seen in Figure 4, results in a bodily forward displacement of the slotted link 188; and this, in turn, results in a clockwise pivotal displacement of the element 195. Following the operation further, the pin 197 on the element 195 displaces the dog 156 forwardly about its pivot and clear of the clutch shifting element 154, thus allowing the latter to move to closed

clutch position under the power of its spring 157, see Figure 12. As heretofore made clear, the platen sub-frame 18 is unlocked and displaced in a single operation by swinging the paper gage 101 forwardly. From this it will be seen that no special attention is required of the operator to render the carbon retracting device effective. After the clutch members 152 and 158 have been engaged, the belt 116 drives the carbon carrier 69 rearwardly until the latter finally engages the aforementioned stop 88 which is adjustably mounted on a straight bar 201 arranged underneath and in parallelism with the direction of movement of the carbon carrier 69. The bar 201 is mounted at opposite ends by pin-and-slot connections 202 upon the carriage extension 45. Reaching downwardly from the bar 201 through one of the openings 46 in the carriage extension is an ear 203 whereto a forwardly extending wire link 204 is connected. The forward end of this link is articulated to a leftward branch 205 of the clutch shifting element 154. In the open clutch position of the latter element, the bar 201 lies in a rearward position, as may be seen in Figures 6 and 11; but whenever the clutch shifting element 154 occupies a closed clutch position, the bar has considerable capacity for rearward movement. As seen in Figure 10, the carrier 69 being power moved rearwardly engages and moves the stop 88, together with the bar 201 and the wire link 204 rearwardly, the latter swinging the clutch shifting element 154 to open the clutch; consequently, the power retraction of the carrier 69 is automatically terminated. As at the conclusion of the power retracting operation, the platen may still be in a displaced position, it is conceived to provide a secondary dog 206 which, incidental to the displacement of the platen sub-frame 18, is automatically conditioned to detain the clutch shifting element 154 against closing movement after being moved to open clutch position. A tail 211 on the pivoted member 195 normally holds the secondary dog 206 clear of the branch 205 of the clutch shifting element. This tail moves leftwardly during the displacement of the platen and the spring 209 then, as far as the tail 211 is concerned, may swing the secondary dog 206 rightwardly. The normal position of the clutch shifting element 154, however, is such that the secondary dog 206 can only swing to holding position in consequence of a clutch opening movement of the shifter 154 somewhat beyond the normal position, as effected by the retraction of the carbon carrier 69, see Figure 9.

Subsequent to the retraction of the carbon sheets 81 and after the work web 83 has been advanced against the gage 102, the operator restores the platen 10 to typing position and severs the typed set of forms by tearing it against the knife 85. A new set of forms is then ready to be typed upon. Incidental to the restoration of the platen sub-frame 18, the parts 181 to 184, 186 to 188 and 195 assume their normal positions seen in Figure 11, so that the said dog 156, which may be termed a primary dog, is free from restraint by the pin 197; and, under the tension of a spring 207, readily assumes its normal effective position against a stop pin 208 to block the clutch shifting element 154 against clutch closing movement. Also incidental to the restoration of the sub-frame 18, but a little later, the secondary dog 206 is forced from effective position by the tail 211 of the pivoted member 195. It will be evident, from an inspection of Figure 10, that the secondary dog 206 detains the clutch

shifting element 154 in a position wherein the primary dog 156 will not be obstructed against movement to effective position. From the foregoing, it should be understood that only one carbon retracting operation can result in response to each displacement of the platen sub-frame 18.

The operator may restore the platen sub-frame before the retraction of the carbon carrier is fully accomplished, and, to prevent rupture of the carbon sheets, which in such an event would become pinched and held against retraction between the feed rolls 26, 27, and the platen, it is highly desirable to terminate the power retraction of the carrier as the platen is being restored to typing position. With this in mind, and with particular reference to Figs. 3, 4, and 12, it will be seen that the clutch-shifting element 154 is adapted to be imparted a clutch-opening movement through a restoration of the dog-controlling element 195 brought about by the restoration of the platen to writing position. More specifically stated, as the point of articulation of the link 181 with the sub-frame sweeps towards the rearward extremity of its moving path, the pin 197 will have moved the clutch-shifting element 154 to an open-clutch position, sufficiently far to allow the primary dog 156 to reassume control thereover and hold it in open-clutch position pending a new displacement of the platen from writing position. Also it may be observed from Figure 11, in conjunction with Figure 3, that the pin 197 recedes from the clutch-shifting element 154 when the platen approaches fully restored position. This is because the point of articulation of the link 181 with the left end piece 24 of the platen sub-frame 18 sweeps past a rearmost point with the result that the link 181, and consequently also the pin 197, is given a slight forward movement just before the said sub-frame reaches the position seen in Figure 3.

The carbon carrier 69 moves rearwardly at considerable speed and, in order to check re-bounding of the carrier from the stop 88, it is conceived to provide automatically responsive means to check the carrier 69 transitorily against advancement following retraction. One embodiment such means may take will now be described with special reference to Figures 6, 10 and 13.

A bell crank 212 is pivoted at 213 to the carbon-carrier truck plate 11 and consists of a hook-shaped arm 214 and a laterally extending arm 215, the latter having pivotally connected thereto a rearwardly extending slide 216. Articulated to the hook-shaped arm 214 and located to the right thereof is an air dash pot device comprising a piston rod 217 pivoted at 218 to the arm 214, a piston 221 rigidly attached to the right end of the piston rod 217, and a cylinder or sleeve 222 which is closed at the right-hand end, except for the provision of a small vent 223. See Figure 13. The sleeve 222 is pivotally mounted on a stud 224 secured to and projecting downwardly from the truck plate 11; and it should be understood that the sleeve aligns itself freely with the angular position of the piston and piston rod as varied by the swinging movement of the arm 212. The slide 216 is guided for fore-and-aft movement and for this purpose has a pin-and-slot connection 225 with the truck plate 11. The pin-and-slot connection normally limits rearward movement of the slide 216, such movement being effected by the power of a light spring 226 that is attached to the arm 214 and anchored to the truck plate 11. When in normal

position, the slide 216 extends rearwardly from the truck plate 71. The piston 221 fits the sleeve loosely and carries a pump washer 227 which readily collapses when the piston moves leftwardly, but which provides an effective seal for the piston when moved rightwardly. It follows, therefore, that the dash pot device functions only when the piston is moved rightwardly, i. e. it functions to delay only the restoration of the arm. The various parts of the rebound checking means normally occupy the positions seen in Figure 6 and it will be observed from this figure that the hook-shaped arm 212 is normally free to move rearwardly with the carbon carrier, without encountering a catch plate 228 which in a forwardly extending relation is attached to the stop 88. During the last portion of the rearward movement of the carrier 69, the slide 216 engages the stop 88 and is displaced forwardly with respect to the carrier 69. The slide 217 being connected to the bell crank 212, the hook-shaped arm swings backwardly of the lug 229 on the catch plate 228. Substantially concomitantly the power retraction of the carrier is terminated, that is, the clutch members 152, 158 become separated and the carrier rebounds forwardly from the stop 88. The hook-shaped arm 214 then temporarily checks rebounding of the carrier by its engagement with the said lug 229. After a certain time interval, as is definitely controlled by the dash pot device, the hook portion of the arm 214, which is of considerable length, clears the lug 229 and the carbon carrier is then free again to move forwardly as required for typing the forms.

The dash pot vent 223 is preferably adjustable so that the duration of effectiveness of the rebound checking device may be varied according to requirement, and to this end, a split ring 235 may be sprung upon the sleeve and adjusted thereupon to cover the air vent 223 to a desirable extent, see Figure 13.

The stop 88 is adjustable along the bar 201 to variously control the positions to which the carbon carrier is retractable. The bar 201 is preferably of light stock; and, in order to counteract flexing thereof, it may be confined on the carbon carrier between the slide 216 and a roller 231.

The motor 95, according to the diagram of Figure 15, need not be continuously running. More specifically, a pair of contact fingers 232 may be included in the motor circuit 233 and may respectively be closed and opened through a link 236, by the clutch-closing and clutch-opening movements of the clutch shifting element 154. A motor switch 234 may also be provided for energizing the motor to effect carriage returns, and may be controlled in accordance with said aforesaid patent to Pitman.

What is claimed is:

1. In a writing machine having a frame, a carriage movable on said frame, and a writing support relatively to which carbon sheets are retractable on said carriage; a motor on said frame, a shaft element disposed in parallel with the direction of movement of the carriage, an element slidably splined to said shaft element, one of said elements being on said frame and rotatable by said motor, and the other of said elements being supported for movement with said carriage, means on the carriage operable to retract said carbon sheets, and including a member that is coaxial with said other element, but normally revolvable independently thereof, and means to operatively connect said last-mentioned element

and said member in any position of the carriage, to cause thereby motor operation of the said operable means.

2. In a writing machine having a frame, a carriage movable on said frame, and a writing support relatively to which carbon sheets are retractable on said carriage; a shaft extending in parallel to the direction of movement of the carriage and being rotatably supported at two spaced locations on said frame, motor drive means to rotate said shaft, an element slidably splined to said shaft for movement along said shaft with said carriage, carriage-supported carbon-sheet retracting means, normally disassociated operatively from said element, and means to shift said element axially on said shaft into driving association with said carbon-sheet retracting means for operating the latter.

3. The combination with a writing machine having a carriage movable on a frame and a carbon carrier on the carriage retractable from a writing support, of means on the carriage operable to retract said carrier, motor drive means to operate said retracting means, including a frame-supported shaft extending in parallel with the direction of movement of the carriage, and a clutch element slidably splined to the said shaft for movement with said carriage, said retracting means including a clutch element companion to the said first clutch element, and means to render the said first clutch element operatively connected or disconnected from the other clutch element in any position of the carriage.

4. In combination with a writing machine having a carriage movable on a frame and a carbon carrier on the carriage retractable from a writing support; a belt drive on said carriage for retracting said carrier, including, a belt operatively connected with said carrier, and a belt moving drum rotatable on a substantially vertical axis; and means to rotate said drum by power, comprising, a motor on the frame, a shaft-member extending in parallel with the direction of movement of the carriage, a member slidably splined to said shaft-member, connecting means between one of said members and said motor, and means to drive said drum by the other one of said members, including, a gear on said carriage, rotatable coaxially with said other member, and a gear on said drum meshing said first gear.

5. In a writing machine having a retractable carbon carrier, power-retracting means for said carrier, including a normally open drive connection, shifting means for opening and closing said drive connection, including means whereby the drive connection is biased to close, means adapted to hold said shifting means in open drive position upon movement thereto, said holding means being normally effective, means operable and restorable, respectively, to disable and enable said holding means, means operative upon the retraction of said carrier to a certain position to move said shifting means to open drive position, and normally ineffective means adapted to detain said shiftable means upon drive opening movement while said holding means remains disabled.

6. In a writing machine having a retractable carbon carrier, a device operable to retract said carrier, power means for operating said device, means movable to and from an operated position to render said power means respectively effective and ineffective to operate said device, said movable means being biased toward operated position, a primary dog normally checking said movable means against operation, control means ac-

tunable to release said primary dog and consequently render said power means effective to operate said device, means, responsive to the retraction of said carrier, to restore said movable means, a secondary dog, rendered effective by the actuation of said control means to check re-operation of said movable means, following restoration, said control means when being restored rendering said primary dog effective and said secondary dog ineffective, said dogs being so arranged that the primary dog will check said movable means against operation following the restoration of said control means.

7. In a writing machine having a platen with respect to which carbon sheets are retractable; a motor, carbon-sheet retracting means operable by said motor and including normally open drive means adapted to be closed to render the carbon-sheet retracting means effective, means mounting said platen for movement to and from a writing position, and means for rendering said drive means closed in response to movement of the platen from writing position, and for rendering it open either in response to movement of the platen toward writing position or in response to the carbon sheets being power-retracted to a certain position.

8. In a writing machine having a platen and a retractable carbon-sheet-carrier; means for mounting said platen for movement from and restoration to a writing position, normally ineffective power-retracting means for said carbon-carrier, including normally open drive-means which are closable to render the power-retracting means effective, means biasing said drive-means to close, holding means normally in control over said drive-means to hold it open, means operative upon said holding means incidental to movement of said platen from writing position to cause closure of said drive-means by said biased means and thereby to render the power-retracting means effective, and means for opening said drive-means either responsive to the retraction of said carrier to a certain position or responsive to the restoration of said platen to writing position, said holding means being so constructed and controlled that responsive to each opening of said drive-means the latter will be held open pending a new movement of the platen from writing position.

9. In a writing machine having a carbon carrier advanceable and retractable from a writing support; belt-drive means associated with said carrier for advancing or retracting it, said drive means including, a drum, and a belt, said belt being operatively connected with said carrier and positively movable by said drum to either advance or retract said carrier; and spring means exerting normally a carbon carrier advancing influence upon said drum.

10. In a writing machine having a carbon carrier advanceable and retractable from a writing support; belt-drive means associated with said carrier for advancing or retracting it, said drive means comprising, a drum, a belt and means to guide a portion of said belt along the moving path of said carbon carrier, said belt being associated for positive movement by the drum to either advance or retract said carrier; spring means exerting normally a carbon carrier advancing influence upon said drum; and means conditionable to power-operate said drum to retract said carbon carrier.

11. In a writing machine having a carbon carrier advanceable and retractable from a writing

support, a drive associated with said carrier for advancing and retracting it including an element rotatable in one direction to cause advance of the carrier, and rotatable in opposite direction to cause retraction of said carrier, power means exerting normally a carbon-carrier-advancing-influence upon said element, normally ineffectively conditioned other power means adapted to rotate said element into said opposite direction, in opposition to the said first power means and means for effectively conditioning the last said power means.

12. In a writing machine having a carbon carrier advanceable and retractable from a writing support, a belt drive for retracting said carrier, comprising, a drum, pulley means, and a belt having opposite ends anchored and wound oppositely on said drum, said belt passing over said pulley means, and said pulley means guiding a portion of said belt along the moving path of said carrier, means operatively associating said belt with said carrier for retracting it, and means normally exerting a carbon-carrier-advancing influence on said drum.

13. In a writing machine having a carbon carrier advanceable and retractable from a writing support, a belt drive for retracting said carrier, comprising, a drum, two guide pulleys spaced in the direction of the movement of the carrier, and a belt having opposite ends anchored and wound oppositely on said drum and having a loop stretched over said guide pulleys, wherefore a portion of said belt extends along the moving path of said carrier, means for supporting said pulleys including a device urging one of said pulleys from the other to keep the belt taut, and means operatively associating said belt with said carrier for retracting it.

14. In a writing machine, a transversely movable carriage, a platen on the carriage, a table, means for supporting and guiding said table in parallel with the direction of carriage movement, means resiliently connecting said table for movement by the carriage so as to allow the table to lag behind the carriage during carriage movements, a carbon-sheet carrier on said table retractable from said platen transversely to the direction of carriage movement, normally ineffectively conditioned motor means adapted to retract said carriage, said motor means including a normally open drive connection on said table in close proximity to the platen carriage, means to displace said platen, and a drive connection controlling mechanism responsive to the displacement of said platen to close said drive connection to render thereby said motor means effective, and responsive to the retraction of said carrier to open said drive connection and to render thereby said motor means ineffective, said controlling mechanism including, a member supported solely on the carriage and operated as an incident to the displacement of the platen, and a member supported solely on the table, said members being constructed and arranged, the former for operation directly by the latter, always to the same extent, irrespective of the variable position of said table with respect to the carriage.

15. In combination with an advanceable carbon-carrier that is limitedly retractable, a device operable to check rebounding advance of the carbon carrier, said device being characterized by a tendency toward ineffective condition, means to operate said device as an incident to the retraction of said carrier to render the device effective as a rebound check, and means for con-

trolling said device to maintain it effective until the rebounding of the carbon carrier has been checked and thereupon render it automatically ineffective.

16. In combination with an advanceable carbon carrier which is limitedly retractive, a device operable and restorable respectively to check rebounding advance of the carrier and to free said carrier for advance, means biasing said device to restore, means to operate said device as an incident to the limited retraction of said carrier to render it effective for rebound checking, and means for controlling the restoration of said device by said biasing means in a manner to keep said device effective substantially long enough only to check rebounding of the carrier, the carbon carrier being thereupon free for advance.

17. In combination with an advanceable carbon carrier which is limitedly retractable, a device operable and restorable, respectively to check rebounding of the carbon carrier and to allow advance of the carbon carrier, means to limit carbon carrier retraction and to cause incidental to limiting the retraction an automatic operation of said device, thereby to render said device effective for rebound checking, and restoration effecting and controlling means for said device constructed to respond automatically but hesitatingly to the operation of said device, so that the latter will automatically allow advance of said carbon carrier, but only after rebounding of the carrier has been checked.

MILES H. MANN.
